FOLDING BOX

William Romano Quagliotti, Victoria, British Columbia, Canada

Application March 8, 1933, Serial No. 660,021

1 Claim. (Cl. 229—52)

My invention relates to improvements in folding boxes and the objects of my invention are to provide a box made entirely in one piece and having a handle, to render the device simple in construction and generally to adapt it to perform better the functions required of it.

I attain these objects in the manner illustrated in the accompanying drawing in which Figure 1 shows a plan of the box before folding and Figures 2 and 3 show plan and end view respectively of the box shown in Figure 1 when folded. Similar letters refer to similar parts throughout.

The box, shown in Fig. 1 before folding, consists of a single piece of cardboard or other suitable material cut so as to form with its central portion the bottom *a* and four sides *b*, *c*, *d* and *e*; it has two projecting parts *g* and *j* on opposite sides, which fold over the top of the box so as to form the top surface; each of these projecting parts has a further projection shaped so as to consist of a handle-piece *k* and a locking flap *l*, formed by cutting the slot *m*; the box also has on the remaining two sides projections *f* and *h* intended to fold over the projections *g* and *j* and each having a slot *n* shaped so as to fit over the two handles *k* and the locking flaps *l* in order that when the box is assembled the flaps *l* will be positioned so as to be engaged by the back of the fingers or thumb and thus be pressed downwardly against the adjacent slotted projection. The dotted lines in Fig. 1 indicate the lines of folding, which may with some weights of material require to be cut slightly on the surface so as to enable folding to be done accurately and easily.

In assembling the box the four sides *b*, *c*, *d*, and *e* are folded into position, the corner parts *o* being folded inwardly. The projections *g* and *j* are next folded over so that they meet and form together the top surface of the box, the parts *k* and *l* being folded in such a way that they stand upright above the upper surface of the box. The slotted sides *f* and *h* are then folded over one at a time and the slots *n* are passed over the parts *k* and *l*, after which the locking flaps *l* are pressed down. This leaves the two parts *k* next to each other forming a handle. Figs. 2 and 3 show the appearance of the box when folded. It will be

seen that by reason of this novel arrangement of parts that when the box or container is in its assembled position, the upper flap *l* will be pressed downwardly by the fingers or thumb and thus insure the parts being maintained firmly in position.

The locking flaps may be folded in opposite directions or in the same direction and may be fastened down if thought necessary, although they should hold satisfactorily without fastening.

It will be obvious that, when not required, as handles, the parts *k* may be folded flat against the top surface of the box.

It should be pointed out that the weight of material used and the shape of the box can be varied greatly according to the purpose for which it is intended. It might be that in some uses of the box it might be found desirable to re-inforce the parts *g*, *j* and *k* or the parts *g*, *j*, *k* and *l* in order to provide additional strength in connection with the handles.

I claim:

A foldable box formed from a blank and having a polygonal intermediate central portion constituting the bottom, opposed pairs of projections extending from the bottom, said projections when folded arranged to form the sides of the box, adjacent projections being connected by corner portions which when folded inwardly along diagonal lines assume a position parallel with the sides of the box, one pair of opposed projections having extensions which when folded, constitute the top of the box, said extensions terminating in handle portions arranged to extend upwardly from the top in adjacent relation and having formed therewith locking flaps, the other pair of projections having slotted extensions arranged to pass over the handles and overlap the top, said locking flaps when the box is assembled arranged to be bent laterally in the same direction to engage the uppermost one of the projections having the slotted extensions, whereby when the handles are gripped by the hand, the thumb or fingers will engage one of the locking flaps to press the flaps against the slotted extension, and thus insure the parts being maintained positively in their folded positions.

WILLIAM ROMANO QUAGLIOTTI.
